CLAIM

The ornamental design for a juggling machete, as shown and described.

DESCRIPTION

FIG. 1 is a first perspective view of a juggling machete showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the juggling machete thereof;

FIG. 10 is an enlarged view of the selected portion 10 in FIG. 1; and,

FIG. 11 is an enlarged view of the selected portion 11 in FIG. 1.

The evenly broken lines shown in the drawings depict portions of the juggling machete that form no part of the claimed design. The dot-dash broken lines shown in FIGS. 1 and 9 are for the purpose of indicating the enlarged partial views and form no part of the claimed design.
